(57) **CLAIM**

I claim the ornamental design for a computing device, as shown and described.

DESCRIPTION

FIG. 1 is a front perspective view of a computing device in an open forward facing and tilted display state;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is a rear perspective view thereof;

FIG. 9 is a front perspective view of the computing device in a closed upward facing display state;

FIG. 10 is a rear perspective view of the computing device in the closed upward facing display state;

FIG. 11 is a front perspective view of the computing device in an open rearward facing display state;

FIG. 12 is a rear perspective view of the computing device in the open rearward facing display state;

FIG. 13 is a front perspective view of the computing device in an open forward facing and upright display state; and,

FIG. 14 is a rear perspective view of the computing device in the open forward facing and upright display state.

The broken lines in the drawings illustrate portions of the computing device and form no part of the claimed design.
